UNITED STATES PATENT OFFICE

LEO L. WEISS, OF NEW YORK, N. Y.

DESIGN FOR A TOY HOUSE OR SIMILAR ARTICLE

Application filed June 9, 1932. Serial No. 44,024. Term of patent 3½ years.

To all whom it may concern:

Be it known that LEO L. WEISS, a citizen of the United States and resident of New York city, in the county of New York and State of New York, has invented a new, original, and ornamental Design for a Toy House or Similar Article, of which the following is a specification, reference being had to the accompanying drawing, forming part thereof, in which the figure is a perspective view of a toy house embodying my new design.

I claim:

The ornamental design for a toy house or similar article, substantially as shown.

Dated, June 8th, 1932.

LEO L. WEISS.
